[57] **CLAIM**

The ornamental design for an eyeglass display rack including rotary disks, as shown and described.

DESCRIPTION

FIG. 1 is a front elevational view of an eyeglass display rack including rotary disks showing my new design;

FIG. 2 is a front perspective view thereof;

FIG. 3 is a rear perspective view thereof;

FIG. 4 is an enlarged perspective view of a single disk, shown separately for ease of illustration;

FIG. 5 is an enlarged fragmentary perspective view of a portion of the rack, the eyeglasses being shown in broken lines for illustrative purposes only; and

FIG. 6 is an enlarged fragmentary perspective view of a portion of the rack viewed from a different angle, with an enlarged showing of a single eyeglass display unit.

FIG. 1

FIG. 2

FIG. 3

FIG. 4

FIG. 5

FIG. 6
